UNITED STATES PATENT OFFICE.

NEAL McLAUGHLIN, OF JETHRO, ARKANSAS.

COMBINED SCRAPER AND SHOVEL-PLOW.

No. 809,626.

Specification of Letters Patent.

Patented Jan. 9, 1906.

Application filed May 15, 1905. Serial No. 260,596.

To all whom it may concern:

Be it known that I, NEAL McLAUGHLIN, a citizen of the United States, residing at Jethro, in the county of Franklin and State of Arkansas, have invented certain new and useful Improvements in a Combined Scraper and Shovel-Plow, of which the following is a specification, reference being had therein to the accompanying drawings.

10 My invention relates to improvements in combined scrapers and shovel-plows, and pertains more particularly to the adjustment of the scraper.

15 The object of my invention is to provide a scraper of this character which is provided with two cutting edges which are precisely alike and which are interchangeable, so that either edge may be used when desired or necessary.

20 Another object of my invention is to provide a scraper of this character in which a smooth outer dirt-engaging surface is maintained and at the same time having the same adjustable and interchangeable, so that either 25 cutting edge may be brought into action and either end may be raised or lowered; also, to provide means whereby the holding means is adjustable on the standard, and thus the blade may be set transverse the beam or at 30 any angle desired.

In the accompanying drawings, Figure 1 is 35 a perspective view of my improved scraper and shovel-plow. Fig. 2 is an enlarged side elevation of my improved blade-attaching means. Fig. 3 is a transverse horizontal sectional view of the blade-attaching means. Fig. 4 is a perspective view of the blade-attaching device detached.

40 Referring now to the drawings, A represents a plow-beam which, as shown, is formed of the two rearwardly-extending arms B and B', which have their rear ends turned downward at b and b'. The downwardly-turned end b of the member B is made of a circular 45 form, as clearly shown in Fig. 2, and which will be hereinafter more fully described. The downwardly-extending end b' of the arm B' is squared, and secured thereto is the shovel-plow C, which may be of any desired structure, but 50 is preferably made of that shown and so arranged that it may be adjusted up or down or at any angle desired. This adjustment is accomplished by the said shovel-plow being provided with a vertical slot c', and passing

through said slot and the arm b' is a bolt D, 55 which firmly holds the shovel-plow in its adjusted position.

The lower end of the arm b, as before described, is rounded for the purpose of allowing the blade-supporting member to be oscillated thereon when the holding means is released. The blade supporting or attaching member consists of an oblong plate E, and which may be either cast or of sheet metal stamped, the latter being the preferred form, 60 as it is less liable to become broken. The said plate E consists of a curved portion F, which is of a curvature to correspond to that of the blade G, and is provided adjacent the upper end with a segmental slot f', and the 65 blade G is provided adjacent each end with two openings g and g', spaced a distance apart equal to the openings f and f', and passing through the blade are the bolts H and H'. The bolt H forms the pivotal point for the 70 blade, and the lower bolt H' passes through the slot f' in the plate and is adapted to travel in the arc of a circle, and thus the blade is 75 adjusted and held in its adjusted position.

The blade G, as clearly shown, is provided 80 adjacent the center with the openings g and g', and thus the blade can be reversed, so that either the cutting edges J or J' may be brought into action, which makes the blade last much longer than with a blade with a single cutting edge.

85 The plate E is provided with a vertically-disposed curved portion I, which is curved at right angles to the curved blade-engaging portion, so as to fit the curvature of the rounded portion b of the beam, and the said rounded portion has a horizontally-arranged elongated slot i, and passing through said slot from the outside before the blade is placed upon the plate is a bolt K, which passes through the rounded portion b of the beam and by means of which the said plate is clamped thereto. It 90 will be seen by loosening the bolt that the plate may be oscillated upon the member b to the extent of the slot, and by this means the angle of the blade is changed in respect to the plow-beam. The lower end of the curved portion I has a forwardly-turned portion L, which extends forward and engages the blades, thus serving as an additional brace for the 95 blade and also serving as a brace for the plate to absolutely prevent the same from being 100 twisted out of its normal shape.

Having thus described my invention, what I claim, and desire to secure by Letters Patent, is—

1. A scraper, comprising a draft-beam, a downwardly-extending arm carried by the beam and having its lower end rounded, a blade-supporting member having a curved portion corresponding to the curve of the beam, means for clamping said plate on the arm, means carried by the plate for securing the blade thereto, and a forwardly-turned portion carried by the curved portion of the plate for engaging and bracing the blade.
2. A scraper, comprising a draft-beam, a downwardly-extending arm carried by the beam and having its lower end rounded, a blade-supporting member having a vertically-disposed curved portion resting against the arm, and having a horizontal elongated slot therein, a bolt passing through the slot and clamping the plate to the arm, one side of said curved portion having a laterally-turned blade-supporting surface, means for adjustably holding the blade thereon, and the opposite edge of said curved portion having a lat-

erally-turned portion engaging the blade and bracing the same.

3. A scraper, comprising a draft-beam, a downwardly-extending arm carried by the beam and having its lower end rounded, a blade-supporting member having a vertically-disposed curved end corresponding to the rounded end of the arm and resting against the same, and having a horizontal elongated slot therein intermediate the upper and lower ends, a bolt passing through the slot and arm and securing the plate to the arm, one side of said curved portion having a forwardly-turned elongated blade-supporting portion, means for adjustably holding the blade thereon, and the opposite edge of said curved portion having a laterally-turned portion engaging the blade and bracing the same.

In testimony whereof I affix my signature in presence of two witnesses.

NEAL McLAUGHLIN.
